UNITED STATES PATENT OFFICE.

JAMES PEARSON, OF BROADHEATH, ENGLAND, ASSIGNOR TO LINOTYPE AND MACHINERY LIMITED, OF LONDON, ENGLAND.

TYPOGRAPHICAL COMPOSING-MACHINE.

1,105,692.

Specification of Letters Patent.

Patented Aug. 4, 1914.

Application filed September 8, 1913. Serial No. 788,506.

To all whom it may concern:

Be it known that I, JAMES PEARSON, a subject of the King of the United Kingdom of Great Britain and Ireland, residing at Linotype and Machinery Works, Broadheath, in the county of Chester, England, have invented new and useful Improvements in Typographical Composing-Machines, of which the following is a specification.

10 This invention relates to improvements in the escapement mechanism of a typographical machine and is especially applicable to a composing machine of the type known commercially under the trade mark "Linotype."

15 It consists in means by which each of a bank of vertical rods forming part of the said mechanism, is automatically moved transversely toward the respective escapement lever to actuate it and back after each actuation, such transverse movements being synchronous with its vertical movements.

20 The accompanying figures illustrate a preferred constructional form of the application of the invention to a four magazine composing machine of the type known commercially under the trade mark "Linotype."

Figure 1 is a sectional side elevation; Fig. 2 one of an alternative detail.

25 The number of magazines is immaterial as far as the invention is concerned. I will first describe it as applied to a single magazine machine. 1 is this magazine; 2, 2, matrices in it; 3, its escapement lever fulcrumed at 4 on the top of the magazine; 5, a spring holding the front one of the two pawls 6, 7, in front of the leading matrix; and 8 the assembler entrance down which the released matrices drop on their way to the assembler, 30 all in the well known way.

35 The usual bank of vertical rods 9 known as escapement rods because they, directly or indirectly, actuate the escapement levers 3, stands for the purpose of the invention, at some distance away from the magazine delivery mouth 10. In the application illustrated, it stands just in front of the assembler entrance 8, and all the rear edges 11 stand in the same vertical plane in order 40 that they may properly coöperate with the slides described farther on. These rods receive the known reciprocating movements, *i. e.* they are raised to release the respective leading matrices and are lowered, after they

have done that, into their normal positions, 55 as heretofore. The transverse movement of a rod 9 toward the respective escapement lever 3 must be synchronous with its upward movement, and is imparted to it by links 12 pivotally connected by their ends respectively to the said rod and to fixed bars 13 extending across the front of the bank of rods. When one of these rods is in its normal position, the links 12 point rearward and downward, as shown in Fig. 1, so that 60 as the rod 9 is raised, the rock of the links 12 on their front pivots as far as the horizontal, moves the said rod transversely toward the respective escapement lever 3. The length of this transversal movement is explained farther on. The links 12 are horizontal when a bar has completed its movement, as indicated by the dot and dash lines in Fig. 1. The number and position of these links 12 is immaterial provided that 75 there are enough, and that they are so positioned as, to produce a true and steady transverse movement. Between each rod 9 and the respective escapement lever 3, there is an intermediate member, the front end of 80 which is in constant contact with the vertical edge 11 of the rod. It is through this member that the transverse movement of a rod 9, makes the respective escapement lever 3 release its leading matrix. It is shown as 85 a slide 14 mounted to reciprocate from front to rear and back, in guides 15 fixed upon the top of the assembler entrance 8. Its position may be horizontal, but with an escapement lever such as the one illustrated and 90 an oblique magazine, its actuation of its lever is facilitated by that position being the oblique one shown.

95 16 is a spring pulling from the assembler entrance 8 upon a slide 14 to keep its front end in operative contact with the edge 11 of its rod 9, and 17 is a shoulder on a slide and engaging with one of the guides 15 to prevent the spring moving it too far in that direction.

100 18 is the operative end of a slide 14 and 19 is a projection on the front end of the respective escapement lever 3. The end 18 and the respective face of the projection 19 are respectively shaped to make engagement 105 easy. They are both shown as being practically horizontal.

20 is a spring pulling from each bar 13

upon each rod 9 to return it to its normal position after its transverse movement has been completed. Thus the return transverse movement of a rod 9 is likewise synchronous with its vertical downward movement.

The action of the invention is as follows: The links 12 move a rod 9 that is being raised for the purpose of releasing a leading matrix, transversely of its length and, consequently, toward the respective lever 3 into the position shown by the dot and dash lines in Fig. 1, and by so doing, push its slide 14 far enough for its end 18 to engage its projection 19, to, in the well known way, rock the respective escapement lever 3 far enough to move its pawl 6 from before the respective leading matrix. The links 12 of a set, are so proportioned and normally positioned, as to terminate the transverse movement of the respective rod 9, as soon as a pawl 6 has been moved from before the said matrix.

The detail shown in Fig. 2, is a substitute for the link device 12 shown in Fig. 1. According to it the transverse movement of a bar 9 is caused by engagement of downwardly and frontwardly directed inclines 21 formed in the bar's front edge, with corresponding inclines 22 on the bars 13.

When a machine of the type above mentioned has a plurality of magazines such as 1, 23, 24, 25, these are arranged columnwise as shown in Fig. 1 with all their delivery mouths 10 in the same vertical plane. In some of these machines the column is stationary in the machine frame, in which case, a single assembler entrance such as 8 is adjustable vertically by suitable means acting through a pitman 26, to enable it to register with the magazine from which the operator wishes to compose. In others, the assembler entrance is itself stationary and the column of magazines is movable up or down in the frame of the machine, to make the said magazine register with the stationary assembler. In either case the projections 19 must be in a plane a little to the rear of the plane containing the mouths 10, and the noses of the ends 18 in a plane a little to the front of the one last mentioned, that little being no more than will keep the noses of the ends 18 on the one hand and the mouths 10 and projections 19 on the other hand, clear of each other when a column or an assembler entrance is moved the one past the other. When it is the assembler entrance 8 that is movable, it is important that the rear edges 11 of the rods 9 are truly vertical in order that the engagements with the sides 14 may all take place in the same vertical plane.

Throughout this specification and the claims, the expressions "matrix," "matrices" are to be understood as including "type die," "type dies" respectively.

Having described my invention I declare

that what I claim and desire to secure by Letters Patent is:—

1. In a typographical machine, the combination of a series of escapements, a series of longitudinally movable actuating rods, means whereby the longitudinal movement of the said rods effects also their bodily edgewise or lateral movement, and a series of members actuated by the edgewise movement of the rods for operating the escapements.

2. In a typographical machine, the combination of a plurality of magazines each provided with a series of escapements, a series of longitudinally movable actuating rods, means whereby the longitudinal movement of said rods effects also their bodily edgewise or lateral movement, and a series of members actuated by the edgewise movement of the said rods for operating the escapements of one or another of the magazines.

3. In a typographical machine, the combination of a plurality of magazines each provided with a series of escapements, a series of actuating rods, and a corresponding series of operating members in engagement with the said rods and movable into operative relation to the escapements of one or another of the magazines and adapted to maintain their operative engagement with said rods during such movement.

4. In a typographical machine, the combination of a series of longitudinally movable actuating rods and a corresponding series of escapement operating members in engagement therewith, the said operating members being movable to different operative positions and adapted to maintain their operative engagement with said actuating rods during such movement.

5. In a typographical machine, the combination of a series of longitudinally movable rods and a corresponding series of escapement operating members slidably engaged therewith so as to be movable to different operative positions and adapted to maintain their engagement with the rods during such movement.

6. In a typographical machine, the combination of a series of longitudinally movable actuating rods, means whereby the longitudinal movement of said rods effects also their edgewise or lateral movement, a plurality of series of escapements and a series of operating members actuated by the edgewise movement of the rods and movable into operative relation to one or another of the series of escapements without affecting their operative relation to the actuating rods.

7. The combination with each escapement of the escapement mechanism of a typographical composing machine, of an escapement rod capable of a reciprocating vertical movement, stationary bars, links pivotally

connected by their respective ends to the rod and bars and capable of moving the rod transversely toward the escapement during the upward movement of the rod, a slide 5 working in fixed guides between the rod and escapement and made by the rod to actuate the escapement when the former is so moved transversely, springs pulling on the rod from the bars to move the rod away from the

escapement during the downward movement of the rod, and a spring to return the slide.

In witness whereof I have hereunto set my hand in the presence of two witnesses.

JAMES PEARSON.
